(57) **CLAIM**

The ornamental design for a leash for animal as shown and described.

DESCRIPTION

FIG. 1 is a first perspective view of a leash for animal showing the new design;

FIG. 2 is a second perspective view thereof;

FIG. 3 is a third perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

In the drawings, the broken lines depict portions of the leash for animal that form no part of the claimed design.

1 Claim, 9 Drawing Sheets
